The ornamental design for electronic computer, as shown and described.

(51) LOC (7) Cl. **14-02**

DESCRIPTION

(52) U.S. Cl. **D14/318**

FIG. 1 is a reduced top, front and right side perspective view of electronic computer showing my new design,

(58) Field of Search D14/318-322;

FIG. 2 is a front elevational view thereof,

D18/1, 2, 7; 235/145 A, 145 R; 341/22,

FIG. 3 is a rear elevational view thereof,

23; 345/104, 156, 168, 169, 173, 538; 361/680-685,

FIG. 4 is a left side elevational view thereof,

690-696; 400/486, 489

FIG. 5 is a right side elevational view thereof,

D431,559 S * 10/2000 Morooka D14/318

FIG. 6 is a top plan view thereof,

D435,549 S * 12/2000 Amano et al. D14/318

FIG. 7 is a bottom plan view thereof,

D453,756 S * 2/2002 Kamegi D14/318

FIG. 8 is a front elevational view showing the article in a closed position thereof,

D479,840 S * 9/2003 Lu D14/318

FIG. 9 is a right side elevational view showing the article in the closed position thereof; and,

6,670,950 B1 * 12/2003 Chin et al. 345/173

FIG. 10 is a top plan view showing the article in the closed position thereof.
